Burnham & Stickney

UNITED STATES PATENT OFFICE.

BURNHAM C. STICKNEY, OF ELIZABETH, NEW JERSEY, ASSIGNOR TO
UNDERWOOD TYPEWRITER COMPANY, OF NEW YORK, N. Y., A COR-
PORATION OF NEW JERSEY.

TYPE-WRITING MACHINE.

No. 811,183.

Specification of Letters Patent.

Patented Jan. 30, 1906.

Original application filed December 16, 1902, Serial No. 136,361. Divided and this application filed June 1, 1903. Serial No. 159,589.

To all whom it may concern:

Be it known that I, BURNHAM C. STICKNEY, a citizen of the United States, and a resident of the city of Elizabeth, county of Union, 5 and State of New Jersey, have invented certain new and useful Improvements in Type-Writing Machines, of which the following is a specification.

This invention relates, primarily, to type-writing machines in which radially-disposed type-bars are arranged about a common printing-point and move one at a time to the printing position. These type-bars, especially in "front-strike" machines, are often 15 closely arranged, so that in rapid operation there is liability of clashing, due largely to the fact that the type-bars are apt to rebound from the basket or cushion upon returning to normal position, thus getting into 20 the path of a subsequently-operated type-bar.

The principal object of my invention, therefore, is to minimize the liability of the type-bars to rebound in this manner.

25 In the drawings forming part of this specification, and in which like signs denote like parts, Figure 1 is a sectional elevation of a type-bar, type-basket, and platen of an under-strike machine, and by turning the figure 30 quarter-way around it will be seen that it represents like parts in a front-strike-machine in which the type-bars lie horizontally and below the plane of the printing-point. Fig. 35 2 is a plan of the type-basket or ring seen at Fig. 1, the type-bars being indicated in cross-section.

A radial series of type-bars 1, carrying types 2, which strike against a platen 3, is supported by hangers 4 upon a ring, segment, 40 or plate 5 and operated by means of pull-rods 6 or otherwise and usually provided with returning-springs. The type-bars normally rest in contact at their type ends with a flexible ring or segment, consisting of a casing 14 45 of some flexibility and preferably tough and inelastic, filled with sand or other force-absorbing material 15, although in some cases the casing need not be entirely filled by the material.

50 The device may be supported in any suitable way, preferably upon inturned fingers 9, formed at the lower edge of a thin stiff sheet-metal ring or band 10, the latter being hung

upon rods 11, attached to the top plate 5 or otherwise supported. In front-strike machines the member 10 may be in the form of a segment and in some cases may be omitted.

The device being flexible yields more or less at the impacts of the type-bars, and owing to this yielding movement some of the adjacent and opposite type-bars are jarred, thereby taking up much of the force of the blow and minimizing the reaction of the parts, so that it does not tend to throw the type-bar back with force, the tendency of the 65 same to rebound being lessened, while owing to the inelastic character of the filling the force of the original blow of the type-bar is still further absorbed, particularly because the filling is incased in soft inelastic material, so that the bar upon striking the basket may possibly drive slightly past its normal position, but will not rebound to the extent of causing it to clash with a subsequently-operated type-bar. This enables the operation of the machine at high speed without 75 danger from this source.

The curved frame or ring 10 is substantial and protects the cushion from injury. It also prevents undue displacement of the 80 cushion. Preferably a narrow space is left at 12 between the ring or segment 10 and the inner member, so as to allow slight freedom of movement of the latter. During such movement there may be more or less friction, 85 between the cushion and the fingers or shelves 9 whereon it is supported, thereby further tending to absorb the force of the type-bar 10.

The filled or partly-filled casing 14 is flexible and inelastic, rendering it desirable for a type-basket, either with or without the stiff ring or segment 10.

Variations may be resorted to within the scope of my invention, and portions of my improvements may be used without others.

Having thus described my invention, I claim:

1. In a type-writing machine, the combination with a series of type-bars of a rest therefor consisting of inelastic material confined within a casing of inelastic pliant material.

2. In a type-writing machine, a type-bar rest consisting of a casing and sand contained therein.

3. In a type-writing machine, a curved type-bar rest consisting of a casing of pliant material and a filling of granular material.
4. In a type-writing machine, the combination with a series of type-bars of a pliant member forming a rest for the type-bars, and a fixed member forming a backing for said pliant member, the latter being capable of a limited bodily movement under the impact 10 of the type-bars.
5. In a type-writing machine, the combination with a series of type-bars of a rest therefor consisting of finely-divided material within a casing of pliant inelastic material, 15 and a fixed curved bar forming a backing for said rest.
6. In a type-writer, a cushion constructed of a yielding sheath and a yielding and non-resilient filling, producing a pad that is 20 absorbent of the energy of the blow struck by the type-bar, and non-resilient under said blow.
7. In a type-writer, a yielding inelastic cushion to support the type-bars in their normal position, consisting of a sheath, and a filling made of finely-divided material.
8. A type-bar cushion comprising a yielding striking-surface and an inherently non-resilient shock-absorbing medium beneath 25 the striking-surface.
9. A type-bar cushion comprising a yielding striking-surface and an inherently non-resilient shock-absorbing medium beneath 30 the striking-surface.
- the striking-surface and movably supporting the same. 35
10. A type-bar cushion comprising a striking surface or facing of yielding material, said material being sufficiently yielding to prevent sudden arrest and consequent rebound or springing of the type-bars, and a non-resilient shock-absorbing backing for said facing, said backing being sufficiently non-resilient to absorb the energy of the returning type-bars, and being also movable so that both the facing and the backing may be displaced by the impacts of the type-bars; said cushion being sufficiently yielding and non-resilient to prevent injurious rebounding of the type-bars therefrom. 40
11. A type-bar cushion comprising a yielding facing of tough material, said facing being inelastic and pliant, and a yielding inelastic shock-absorbing backing; said cushion being sufficiently yielding, inelastic and shock-absorbing to prevent injurious rebounding of the type-bars. 45
12. A type-bar cushion comprising a facing of inelastic, pliant leather, and a yielding, inelastic shock-absorbing backing; said cushion being sufficiently yielding, inelastic and shock-absorbing to prevent injurious rebounding of the type-bars. 50
